[57] CLAIM

The ornamental design for a vehicle bumper, as shown and described.

DESCRIPTION

FIG. 1 is a perspective view of a vehicle bumper in accordance with the present invention;

FIG. 2 is a front elevational view of the vehicle bumper shown in FIG. 1;

FIG. 3 is a top plan view of the vehicle bumper shown in FIG. 1; and,

FIG. 4 is a left side elevational view of the vehicle bumper shown in FIG. 1, with the right side elevational view being a mirror image thereof.
